HYDRODEALKYLATION OF SPECIAL
FEED STOCKS

William Newton Kestner, Baton Rouge, La., assignor to
Esso Research and Engineering Company, a corpora-
tion of Delaware
No Drawing. Filed June 19, 1961, Ser. No. 117,808
7 Claims. (Cl. 260—672)

The present invention relates to a combined steam cracking and hydrodealkylation process for economically producing both the ordinary olefins and diolefins obtained conventionally from high conversion steam cracking, and pure aromatic materials, e.g. naphthalene. More particularly, this invention relates to steam cracking heavy virgin crude oils or selected fractions of the products from catalytic cracking e.g. light catalytic cycle oil under severe conditions to crack substantially all of the paraffins present and feeding the aromatic concentrate so prepared to hydrodealkylation to prepare e.g. naphthalene and also small amounts of benzene. Most particularly, in a preferred embodiment, this invention relates in such a process to severely steam cracking such feeds boiling in the range of 400 to 650° F. under conditions to obtain 25 to 45 wt. percent conversions to C_3^- materials.

Process for the hydrodealkylation of alkyl substituted aromatic compounds are well-known and widely used at the present time. These processes are both of the thermal non-catalytic type and of the catalytic type, e.g. utilizing a chromia on alumina catalyst. A preferred method for carrying out the thermal non-catalytic hydrodealkylation is described in S.N. 91,832, filed February 27, 1961. In all of these processes hydrodealkylation is obtained with a consumption of at least 1 mole of hydrogen per alkyl group due to the breaking off of the alkyl side chain to form the aromatic compound and a saturated aliphatic paraffin. Feed stocks for these processes are, of course, conventionally obtained from crude oil, catalytic reformate, catalytic cycle oils, etc. which have been extracted to concentrate the aromatic fraction. Thus, in the hydrodealkylation process it is ordinarily necessary to extract to limit the amount of paraffins and olefins present which otherwise are cracked to predominantly methane with the consumption of large amounts of hydrogen. This is undesirable in that expensive hydrogen is consumed to form cheap products of small sales value.

It has now surprisingly been discovered that excellent feed stocks for hydrodealkylation may be obtained by steam cracking at high conversions specific feed stocks to thus obtain not only the conventional olefins and diolefins obtained from steam cracking but also superior naphthalene precursors to those obtained from conventional SO_2 , phenol, etc. extraction. Thus, in these extraction processes the extract contains considerable non-aromatic material as side chains. In steam cracking valuable olefins and diolefins are made from the fracture of the aromatic side chains as well as from the non-aromatic portion of feed stocks. This is compared with the cheap methane produced and high hydrogen consumption which would be obtained if an extraction process were used to concentrate the aromatics. An additional advantage of the present process is that desulfurization prior to steam cracking may be used without detriment since the tetalins

2

so formed are dehydrogenated back to alkyl naphthalenes in the steam cracking step. Thus, it is known that alkyl naphthalenes give considerably higher selectivities to the desired naphthalene in hydrodealkylation.

Preferred feed stocks to be fed to steam cracking according to this invention boil in the range of 300 to 800° F. These feed stocks contain alkyl naphthalene, naphthalene, alkyl tetalins, alkyl benzenes, paraffins and small amounts of olefins. Preferred aromatic hydrocarbon feeds are suitably obtained from crude petroleum from catalytic cracking and less preferably from catalytic reforming.

Preferred feed stocks from catalytic cracking boil in the range of 400 to 850° F., preferably 430 to 590° F., e.g. 430 to 560° F.; and contain 15 to 30 wt. percent, preferably 20 to 30 wt. percent, e.g. 30 wt. percent naphthalenes and alkyl naphthalenes; 2 to 6 wt. percent, preferably 4 to 6 wt. percent, e.g. 6 wt. percent alkyl tetalins; 3 to 24 wt. percent, preferably 10 to 24 wt. percent, e.g. 24 wt. percent, alkyl benzenes; and 40 to 80 wt. percent, preferably 40 to 60 wt. percent, e.g. wt. percent paraffins and olefins. A description of a preferred catalytic cracking process is contained in U.S. 2,589,124. Preferred feeds to said catalytic cracking process boil in the range of 475 to 1050° F., e.g. 600 to 900° F. to produce feeds for the present process.

From crude oil preferred fractions boil in the range of 300 to 850° F., preferably 400 to 800° F., e.g. 500 to 750° F.; and contain 8 to 30 wt. percent, preferably 20 to 30 wt. percent, e.g. 30 wt. percent naphthalenes and alkyl naphthalenes; 4 to 20 wt. percent, preferably 8 to 20 wt. percent, e.g. 20 wt. percent alkyl tetalins; 2 to 15 wt. percent, preferably 5 to 15 wt. percent, e.g. 15 wt. percent alkyl benzenes; and 35 to 70 wt. percent, preferably 35 to 50 wt. percent, e.g. 35 wt. percent paraffins and olefins. Preferred crude oils are those having a high aromatic content obtained for example from San Joaquin (Venezuelan) or Tia Juana (Venezuelan) crude or Aramco (Near East) crude.

A less preferred feed stock is obtained from hydroforming, preferably platinum hydroforming. These feeds boil in the range of 300 to 700° F., preferably 400 to 650° F., e.g. 430 to 560° F.; and contain 20 to 40 wt. percent naphthalenes and alkyl naphthalenes; 2 to 6 wt. percent, preferably 4 to 6 wt. percent, e.g. 6 wt. percent, alkyl tetalins; 20 to 40 wt. percent, preferably 30 to 40 wt. percent, e.g. 40 wt. percent alkyl benzenes; and 14 to 50 wt. percent, preferably 14 to 20 wt. percent, e.g. 14 wt. percent, paraffins and olefins. A description of a preferred process for platinum hydroforming is contained in U.S. 2,902,427. Preferred feeds to said platinum hydroforming boil in the range of 300 to 600° F., e.g. 340 to 500° F. to produce feeds for the present process.

Steam cracking is conducted at temperatures in the range of 1100 to 1500° F., preferably 1200 to 1490° F., e.g. 1400° F., pressures of 1 to 20 p.s.i.g., preferably 1 to 10 p.s.i.g., e.g. 5 p.s.i.; for residence times of .1 to 1.0 second, preferably .1 to .4 second, e.g. .2 second, and utilizing amounts of steam in the range of 50 to 90 moles, preferably 60 to 80 moles, e.g. 75 moles per 100 moles of feed.

Preferred conversions to C_3^- are controlled in the range of 20 to 60 wt. percent, preferably 25 to 55 wt. percent,

e.g. 35 wt. percent. The products from the steam cracking zone are immediately quenched and are separated by fractionation to remove the desired fraction to be fed to the hydrodealkylation reactor. This fraction may be a broad cut boiling in the range of 160 to 600° F., preferably 200 to 590° F., e.g. 220 to 560° F. (used to prepare both e.g. naphthalene and benzene) or alternatively may be a narrow cut containing only the naphthalene precursors boiling in the range of 400 to 600° F., preferably 420 to 590° F., e.g. 430 to 560° F. It should be noted that the alkyl benzene material boiling at a lower temperature than the naphthalene precursors will be valuable either for the separation of pure components, e.g. ethyl benzene from this fraction or for feeding it separately or with the naphthalene precursors to hydrodealkylation to produce benzene.

Hydrodealkylation is conducted at temperatures in the reaction zone controlled in the range of 1100 to 1600° F., preferably 1150 to 1400° F., e.g. 1150 to 1375° F., pressures of 500 to 1000 p.s.i.g., preferably 400 to 700 p.s.i.g., e.g. 600 p.s.i.g., and for reaction times of 2 to 120 seconds, preferably 2 to 100 seconds, e.g. 50 seconds. Preferably the reaction is carried out in a reaction zone having a high L/D ratio, preferably 40:1 to 150:1, e.g. 65:1, and utilizing a hydrogen quench to control the temperature of the reactants, all as described in S.N. 91,832 filed February 27, 1961. The amount of hydrogen-containing gas initially supplied is 1 to 6 moles, preferably 2 to 4 moles, e.g. 3 moles per mole of the alkyl aromatic material contained in the feed. The hydrogen-containing gas according to the present invention should contain above 50% hydrogen, preferably above 80%, more preferably above 90%, e.g. 92% hydrogen. In a preferred embodiment the amounts of hydrogen above described are initially supplied and additional amounts of hydrogen are supplied at quench points to control the reaction temperature in the reaction zone below 1300° F. The amount of additional hydrogen added in this embodiment is 2 to 15 moles, preferably 3 to 10 moles, e.g. 7 moles per mole of aromatic material in the feed. In general, all the preferred procedures described in S.N. 91,832, filed February 27, 1961, may be used in the present process. Reaction products from the hydrodealkylation reaction are immediately quenched and the desired pure naphthalene and other aromatic compounds are separated by distillation.

The present invention will be more clearly understood from a consideration of specific examples showing preferred methods for carrying out the present invention.

Example 1

A feed stock boiling in the range of 430 to 600° F. obtained from the catalytic cracking of a 500 to 990° F. gas oil from South Louisiana crude is fed to a steam cracker operated under the following conditions.

Temperatures----- 1400° F. coil outlet.
Pressures----- 12 p.s.i.g. at coil outlet.
Residence times----- .3 second above 900° F.
Amount of steam/100 moles of feed----- 75 moles.

Product gases from the steam cracker after quenching and separation of water are fractionated to separate an aromatic concentrate boiling in the range of 430 to 590° F. This feed is fed to the hydrodealkylation process and contains 17 wt. percent paraffins, 13 wt. percent alkyl benzenes, 19 wt. percent indanes, 35 wt. percent alkyl naphthalenes, 3 wt. percent tetralins and 14 wt. percent other aromatics such as acenaphthene and phenanthrene boiling in this range. This feed is supplied with 3.1 moles per mole of feed of a 92% hydrogen stream (the remainder being essentially methane) to a furnace at a temperature of 850° F. In this furnace the combined stream is heated to a temperature of 1100° F. in approximately 3 seconds. The 1100° F. stream is supplied to an internally lined 65:1 L/D reactor operating at 600 p.s.i.g.

wherein in the first section the temperature rises to 1225° F. and is quenched with the same 92% hydrogen-containing gas to a temperature of 1150° F. This quench gas is supplied at 130° F., and the amount of the gas is 1.5 moles per mole of feed. At the second quench point the temperature is 1260° F. and 2.2 moles of the hydrogen-containing gas per mole of hydrocarbon feed (introduced at the same temperature as above) is utilized to cool the reactants to 1160° F. At the third quench point the temperature is 1310° F. and 3.5 moles of the same hydrogen-containing gas per mole of hydrocarbon feed, again at the same temperature, is used to cool the reactants to a temperature of 1160° F. The final quench is with recycle gas from the process without hydrogen enrichment containing 60 mole percent hydrogen, the remainder being light hydrocarbons and principally methane. This gas is supplied at a temperature of 100° F. and the amount of the final quench gas is 4.4 moles per mole of reactants. This quench rapidly cools the gases to a temperature of 1150° F. The approximate vapor velocity in the reactor varies from 1.5 at the inlet to 4.5 feet/second at the outlet and the contact time is about 50 seconds. For these conditions, about 95% of the alkyl aromatics are dealkylated into the desired product of benzene and naphthalene.

25

Example 2

A feed stock boiling from 420 to 589° F. obtained from the catalytic cracking of a 490 to 1050° F. gas oil from a mixture of South Louisiana, North Louisiana and Louisiana-Mississippi crudes was fed to a steam cracker operating under the following conditions.

Temperature----- 1420° F. coil outlet.
Pressure ----- 10.8 p.s.i.g. at coil outlet.
Residence time----- 0.25 second above 900° F.
Amount of steam----- 77 mole percent on feed.

Product gases from the steam cracker after quenching and separation of water were fractionated to separate an aromatic concentrate boiling from 424 to 579° F. The yield of this material was 17.4 wt. percent on steam cracking feed.

It is to be understood that this invention is not limited to the specific examples, which have been offered merely as illustrations, and that modifications may be made without departing from the spirit of this invention.

What is claimed is:

1. The combined steam cracking and hydrodealkylation process which comprises steam cracking at high conversions a product stream from catalytic cracking boiling in the range of 300 to 850° F., distilling the reaction products from the said steam cracking to separate an aromatic concentrate fraction boiling within the range of 160 to 600° F., hydrodealkylating the said aromatic concentrate fraction at temperatures in the range of 1100 to 1600° F., and separating a dealkylated aromatic from the reaction products from the said hydrodealkylation.
2. The process of claim 1 in which steam cracking is carried out at severities to obtain C₃- conversions of 20 to 60 wt. percent.
3. The process of claim 1 in which the feed stock is an oil obtained from the products from catalytic cracking of a gas oil boiling in the range of 475 to 1050° F., the said oil being a fraction selected within the boiling range of 400 to 850° F.
4. The process of claim 1 in which the product stream from catalytic cracking is obtained from a catalytic cracking process in which a part of this product stream is recycled in the catalytic cracking operation.
5. The process of claim 1 in which hydrodealkylation is carried out thermally in the absence of a catalyst at temperatures in the range of 1150 to 1400° F.
6. The process of claim 1 in which the aromatic concentrate fraction is a fraction selected within the boiling range of 160 to 600° F.
7. The combined steam cracking and hydrodealkylation

75

process which comprises steam cracking at high conversions to C_3^- in the range of 25 to 55 wt. percent a product stream from catalytic cracking boiling within the range of 430 to 590° F., distilling the reaction products from the said steam cracking to separate an aromatic fraction boiling within the range of 420 to 590° F., hydro-dealkylating the said aromatic concentrate fraction at temperatures in the range of 1150 to 1400° F., pressures of 400 to 700 p.s.i.g. for reaction times of 2 to 100 seconds

in a reaction zone having an L/D ratio in the range of 40:1 to 150:1 and separating a dealkylated aromatic from the reaction products from the said hydrodealkylation.
